UNITED STATES PATENT OFFICE

155,616

DESIGN FOR A CLOCK CASE OR SIMILAR ARTICLE

Abraham Levy, Brooklyn, N. Y., assignor to United Metal Goods Manufacturing Co. Inc., Brooklyn, N. Y., a corporation of New York

Application May 19, 1948, Serial No. 146,470

Term of patent 7 years

(Cl. D42—7)

To all whom it may concern:

Be it known that I, Abraham Levy, a citizen of the United States, residing at Brooklyn, New York, in the county of Kings and State of New York, have invented a new, original, and ornamental Design for a Clock Case or Similar Article, of which the following is a specification, reference being had to the accompanying drawing, forming part thereof.

Fig. 1 is a front view of a clock case, showing my new design.

Fig. 2 is a side view thereof.

The essential features of the design are shown in full lines, such essential features being the rolling pin grasped in the right hand of the figure, the handle of the skillet grasped in the left hand of the figure, with the outer part of the

skillet forming the circular border around the face of the clock; the bow tie and the upturned feet of the figure.

I claim:

The ornamental design for a clock case or similar article, as shown and described.

ABRAHAM LEVY.
